ATTEST.

UNITED STATES PATENT OFFICE.

FREDERICK ELIJAH BLAISDELL, OF KENSINGTON, LONDON, ENGLAND.

PRINTING-MACHINE.

No. 927,699.

Specification of Letters Patent.

Patented July 6, 1909.

Application filed December 4, 1906. Serial No. 846,232.

To all whom it may concern:

Be it known that I, FREDERICK ELIJAH BLAISDELL, citizen of the United States, residing at 105 Oakwood Court, Kensington, London, England, have invented new and useful Improvements Relating to Printing-Machines, of which the following is a specification.

This invention relates to improvements in contrivances for dealing with a rapid succession of sheets of paper which become wet with an ink impression from a printing machine, the sheets being dealt with in such a way as to cause them to be deposited in a manner adapted to avoid off-setting and smearing.

The chief distinguishing features of my invention are as follows: The method of operation involves the employment of a reciprocating carrier which takes a sheet as delivered wet from a printing machine and conveys it to a position over a pile and having dropped it thereon returns for the next sheet and so on in succession. The carrier is conveyed along guiding arms and these arms, which are pivotally mounted, are, after the delivery of a sheet, so displaced that the succeeding sheet is delivered on to another pile and the next sheet to still another pile and the following to yet another, the total number of piles thus formed being four as illustrated in the accompanying drawings, though a larger or a less number may be adopted.

To carry out the operation above described in a compactly arranged machine which occupies a minimum amount of floor space, I arrange the pile supports one over the other with only sufficient space between them to permit of the accumulation of a moderate number of sheets and the transit of the carrier above the pile which will gradually form thereon. In order to convey a sheet into the comparatively narrow space between the piles without contact with a sheet deposited thereon the corresponding portion of the guide of the carrier is required to be adapted to be set and maintained parallel to the supports and moreover it is required to be so mounted that, between each delivery, it can rise or descend from the former place of delivery. For this purpose, this portion of the carrier-guide consists of two outstretched arms sufficiently wide apart to allow them to include between them the width of the pile supports which are secured at one end to the frame of the machine and overhang there-

from. The outstretched arms are raised and lowered by being pivotally mounted on the free end of an angularly displaceable cantilever, the two portions being connected together by a parallelogram mechanism of the parallel-ruler type whereby the outstretched arms are maintained horizontal.

By having a plurality of piles, the time interval between the deposit of consecutive sheets on the same pile will be such a multiple of the time interval between the delivery of consecutive sheets from the printing machine as, in many cases, to allow sufficient time for the ink to set. At any rate the time interval will be sufficient to allow a pile to be removed and a fresh board provided on the pile support before the next sheet will be delivered thereto, thus, without delaying the operation of the printing machine, the necessity for the accumulation of many sheets on one pile will be avoided and thus a tendency to off-setting due to superimposed weight will be eliminated.

To carry out the above described fundamental operations with precision and certainty a number of devices are adopted in the construction of the machine and some of these are claimed in the final claims, but it is to be understood that these specific devices are not essential to the invention, for their functions may be performed by various mechanical equivalents.

The accompanying drawings show a form of construction adapted to carry out the operations above referred to.

In these drawings:—Figure 1 is a side elevation showing the apparatus fitted to a printing machine of known type whose frame is adapted to carry the operative members of the paper piling contrivance. Fig. 2 is a plan. Fig. 3 is a plan of a part of the sucker strip secured to the carrier. Fig. 4 is a section of the sucker strip taken along the line 4—4 of Fig. 3. Figs. 5 and 6 are respectively a sectional plan and elevation of a component of a sheet retaining device. Fig. 7 is an enlarged elevation of a portion of the cantilever lifting gear.

In these figures *a* is the cylinder of a printing machine which, revolving in the direction of the arrow (Fig. 1), delivers the printed sheet wet-face uppermost onto tapes *b*¹ and *b*² which are caused to travel continuously in one direction by the rotation of a roller *b*³ driven by the pitch-chain *b*⁴ and chain-wheel *b*⁵. From the tapes the wet sheet is

taken to the pile or piles by pneumatic attachment to a carrier to be subsequently described, which is caused to undergo a longitudinal reciprocating movement derived from the quadrant c and transmitted through the pinion c^1 and chain-wheels d^1 , d^2 and d^3 and pitch-chains. The quadrant c obtains an alternating angular movement by means of a rack e^1 and pinion e^2 from a stud-pin f on the face of a continuously revolving wheel f^1 secured to a cross-shaft which is actuated from the other side of the machine by the motor which drives the printing machine.

Pivotedly mounted on the frame of the printing machine is a compound cantaliver, whose axis is co-incident with that of the pinion c^1 and chain wheel d^1 . The cantaliver consists of a pair of arms g to each of which is secured a quadrant g^1 fitted with a pitch-chain g^2 secured to the end g^3 of the quadrant, the pitch-chain serving as a medium for effecting the angular displacement of the cantaliver and also as a means of suspension of a counter-balance weight g^4 .

Pivotedly mounted on the ends of the arms g , having its axis co-incident with that of the chain-wheel d^3 , is a second pair of arms h which, by means of links i mounted on an axis i^1 situated vertically above the axis of the pivot of g and so secured to the arms h as to be always parallel to the arms g , will be constrained to remain always horizontal in all angular positions of the arms g . The arms h are separated laterally from one another sufficiently to permit them to rise and descend and inclose between them a series of superposed overhanging shelves j^1 , j^2 , j^3 , j^4 which are secured to and project from the frame j .

In Fig. 1 the compound cantaliver is shown in full lines in its lowest position and in dotted lines in a position suitable for depositing a sheet on shelf j^3 .

The raising and lowering of the cantalivers is effected by means of a cam k which actuates a lever m which carries a roller m^1 , the lever being connected to a rod n formed with a rack n^1 at its upper end. The rack n^1 gears with a pinion o secured to a cross shaft o^1 to which also is secured at each end a toothed wheel o^2 which on each side of the machine engages with the before mentioned pitch-chain g^2 . The cam k derives its motion of continuous rotation from the before-mentioned spur-wheel f^1 through the medium of wheels f^2 , f^3 and f^4 to which latter the cam is secured and which, riding on the motor driven cross-shaft, revolves at one-fourth the speed of that shaft. Referring to Figs. 1 and 7, it will be seen that the cam k is formed with four steps. When the circular portion k^1 is in contact with the roller m^1 the cantaliver will be in its lowest position. The cam revolving in the direction of the arrow, Figs. 1 and 7, will cause the roller to pass

into engagement with the circular portion k^4 at which time the cantaliver will have been raised into a position for the deposit of a sheet on shelf j^2 . A step of double amplitude will next be performed, the cantaliver being thereby raised to the top shelf j^3 , the circular portion k^4 of the cam then engaging with the roller. From this position the cantaliver will descend, first by a single step to the shelf j^4 , when the roller engages with k^3 and, afterward, by a double step to the shelf j^1 , and so on in succession. According to this sequence the greatest rise and fall of the cantaliver on each movement will be minimized.

Along guides provided in the arms of the cantaliver a flexible carrier is caused to reciprocate, there being a chain p^1 connected by one end to the left-hand end of the carrier (Fig. 1) the other end being wrapped around and secured to a pulley p which is itself secured to the cross-shaft which carries the before-mentioned chain-wheel d^4 which is alternately rotated in opposite directions. A second chain is fastened at one end to the right-hand end of the carrier and is wound in the opposite direction around the same pulley and secured thereto. This arrangement being provided in duplicate, one on each side of the machine, the carrier will reciprocate as the before mentioned quadrant c vibrates. The carrier comprises a number of cross spindles p^2 fitted with rollers to run in the guides of the compound cantaliver and connected at each end by a chain of links p^3 . The carrier supports two flexible strips q of rubber having a number of orifices formed in their under surfaces, which orifices serve as sucker mouths for pneumatic attachment to the borders on the upper face of the wet printed sheet.

Referring to Fig. 4 which shows a section of the strip q taken along the line 4-4 of Fig. 3, the strip is shown as composed of three thicknesses which are cemented together. In the strip are formed two longitudinal passages q^1 and q^2 which are closed at the ends and which, at the end away from the printing machine, are joined by a transverse passage q^3 . At intervals along the length of the strip, holes q^4 are bored and these open into sucker mouth-pieces q^5 of enlarged diameter. The passage q^1 being connected to a space in which a vacuum is maintained, then, by means of the transverse passage q^3 , there will be a tendency to the production of a vacuum in the passage q^2 and in the sucker mouth-pieces q^5 . The vacuum will be most intense in the mouth-pieces near the transverse passages q^3 and these will be the first to come into contact with the wet sheet to be conveyed, near the leading edge thereof, when the carrier has commenced its movement away from the printing cylinder. As the mouth-pieces become successively closed by the adherence of the paper the

vacuum in that next in succession will become intensified.

To provide for a variety of widths of printed sheets the sucker strips q are suspended from the spindles p^2 in a manner which will permit of adjustment of their distance apart. To facilitate the adjustment and maintain connection with the vacuum space a cross tube r^1 , secured to the carrier, is connected at one end to a shorter parallel tube r^2 and at the other end to a similar parallel tube r^3 . Into one of the tubes r^2 r^3 is inserted, in a telescopic fitting manner, a tube connected to the passage q^1 of one of the strips and into the other a similar and similarly fitted tube connected to the passage q^2 of the other strip. The tube r^1 being connected to the vacuum at r^4 by swiveling and telescoping tubes r^5 r^6 , the sucker mouths will always be ready to seize the printed sheet when it comes in contact therewith. By a cam, not shown, it is arranged for the vacuum to be broken in the tube r^1 at the instant the carrier has completed its outward movement. To insure the accurate deposit of the conveyed sheet, a pair of adjustably fixed suckers s^1 , (Figs. 2 and 6), are provided with which the upper surface of the leading edge of the conveyed sheet comes in contact at the instant preceding the breaking of the vacuum in the sucker strips. The suckers s^0 are connected to a valve box s which is in communication with the vacuum space by a system of telescoping tubes s^1 s^2 s^3 arranged in the manner of the before mentioned tubes r^1 r^2 r^3 , to permit of adjustment of the positions of the suckers s^0 to suit the width of the sheet of paper being printed. In the valve box s is fitted the tubular valve s^4 which, when the port s^5 , formed therein, coincides with the port s^6 in the valve-box by the pressure of the carrier on the buffer s^7 effecting the compression of the spring s^8 , causes the formation of a vacuum in the suckers s^0 . On the retreat of the carrier the valve s^4 will tend to return under the action of the spring s^8 but will be prevented so long as a vacuum is maintained within the valve s^4 . After the carrier has removed itself from beneath the sheet the vacuum will be broken in the pipe leading from the port s^6 to the vacuum space by a suitable cam-operated valve (not shown) and the sheet will be allowed to drop. A set of suckers and connections S^0 — s^0 is provided above each of the shelves, all the valve-boxes being united to a common standard s^9 which is in connection with the vacuum space.

Claims.

60 1. Means for conveying wet sheets from a printing machine to automatically deposit them on a pile without smearing, comprising two longitudinal rows of pneumatic suckers, a passage from a permanent vacuum space to the leading sucker mouth of each row and

a passage therefrom extending from the leading sucker successively to those which follow.

2. Means for conveying wet sheets from a printing machine to automatically deposit them on a pile without smearing, comprising two longitudinal rows of pneumatic suckers the inmouths of which are separately connected with the vacuum space by a constricted passage, a passage from a permanent vacuum space to the leading sucker mouth of each row and a passage therefrom extending from the leading sucker successively to those which follow.

3. For conveying wet sheets from a printing machine to deposit them on one or more piles, a flexible carrier comprising two longitudinal rows of pneumatic suckers, a plurality of parallel cross-spindles which carry the pneumatic suckers, supporting rollers at the ends of the spindles and a pair of chains of pivotally connected links which join together the ends of the several spindles.

4. For conveying sheets from a printing machine to deposit them on one or more piles, a combination of a flexible carrier, organs of attachment to the borders of the sheets carried thereon, a guide for the carrier made in two portions, means for reciprocating the carrier along said guide and means for angularly displacing the two portions of the guide relatively to each other.

5. For conveying wet sheets from a printing machine to automatically deposit them on a pile without smearing, a combination comprising two rows of pneumatic suckers, a reciprocating carrier therefor and means for connecting the suckers with a pneumatic vacuum space comprising a swiveling telescoping tube and a pair of parallel transverse telescoping tubes.

6. For conveying wet sheets from a printing machine to automatically deposit them on a pile without smearing, a combination comprising two longitudinal rows of pneumatic suckers, a flexible reciprocating carrier therefor, means for automatically and periodically making and breaking a vacuum in the suckers and a pneumatic organ of detention adapted to seize and hold the leading edges of the sheets during the return movement of the carrier.

7. Apparatus for conveying and automatically piling a succession of sheets from a printing machine on a plurality of piles, comprising a longitudinally reciprocating carrier, a guide for the carrier, supports for the piles and means for angularly displacing the carrier-guide relatively to the pile-supports.

8. In apparatus for conveying and automatically piling a succession of sheets from a printing machine on a plurality of piles, a cantaliver for guiding a sheet-carrier, comprising a pivoted branch angularly dis-

placeable in a vertical plane, an overhanging pair-armed branch, pivotally mounted on the extremity of the said angularly displaceable branch, and means for maintaining the overhanging branch in an approximately horizontal position for all angular positions of the first mentioned branch of the cantaliver.

9. In apparatus for conveying and automatically piling a succession of sheets from a printing machine on a plurality of piles, a cantaliver for guiding a sheet-carrier, comprising a pivoted branch angularly displaceable in a vertical plane, an overhanging pair-armed branch, pivotally mounted on the extremity of the said angularly displaceable branch, and a parallelogram mechanism for maintaining the overhanging branch in an approximately horizontal position for all angular positions of the first mentioned branch of the cantaliver.

10. In apparatus for series-piling, a combination comprising a plurality of overhanging superposed pile-supports, an angularly

displaceable cantaliver and a stepped organ 25 for directing the cantaliver to each pile in turn, the maximum displacement of the cantaliver between any two consecutive deliveries corresponding to twice the space interval between two consecutive pile-supports.

11. In apparatus for series-piling, a combination comprising a plurality of overhanging superposed pile-supports and an angularly displaceable cantaliver for directing the 35 sheets to be piled, which cantaliver comprises a pair of outstretched arms, which enclose the pile-supports between them, and mechanism for maintaining the said arms in an approximately horizontal position for all 40 angular positions of the cantaliver.

In testimony whereof I have signed my name to this specification in the presence of two subscribing witnesses.

FREDERICK ELIJAH BLAISDELL.
